DESIGN FOR A CAMERA

James E. Harvey, Ann Arbor, Mich., assignor to
Argus, Incorporated, Ann Arbor, Mich., a corporation of Michigan

Application November 21, 1947, Serial No. 142,717

Term of patent 14 years

(Cl. D61—1)

To all whom it may concern:

Be it known that I, James E. Harvey, a citizen of the United States, residing at Ann Arbor, in the county of Washtenaw and State of Michigan, have invented a new, original, and ornamental Design for a Camera, of which the following is a specification, reference being had to the accompanying drawing, forming a part thereof.

Figure 1 is a front elevational view of a camera, showing my new design;

Figure 2 is a top plan view;

Figure 3 is an elevational view of the left side of the camera; and

Figure 4 is a fragmentary rear elevational view of the top portion of the camera.

I claim:

The ornamental design for a camera, as shown.

JAMES E. HARVEY.
